LINING FOR SINKS OR THE LIKE

Andrew W. Robertson, Pittsburgh, Pa., assignor
to Westinghouse Electric Corporation, East
Pittsburgh, Pa., a corporation of Pennsylvania

Application February 24, 1945, Serial No. 579,543

2 Claims. (Cl. 4—183)

1

My invention relates to sinks, more particularly to kitchen sinks, and it has for an object to provide a protective lining or insert therefor, which lining may be readily applied to the sink and removed therefrom.

In accordance with the invention, I provide, as a new article of manufacture, a lining of the character set forth, which, being formed of a resilient material such as natural or synthetic rubber or other plastics, will closely conform to the wall members of the sink and define a cushioning covering for the wall members whereby breakage and chipping of china and glassware which are cleansed in the sink are substantially reduced. Furthermore, the lining protects the vitreous finish on the sink against stains or chipping and permits the washing of dishes and pans with less clatter than usually accompanies this operation.

The foregoing and other objects are effected by my invention as will be apparent from the following description and claims taken in connection with the accompanying drawings forming a part of this application, in which:

Fig. 1 is a perspective view of a kitchen sink having a lining constructed in accordance with my invention applied thereto;

Fig. 2 is a view similar to Fig. 1 showing a double basin liner applied to a single basin sink;

Fig. 3 is a perspective view of a double basin sink having a double basin liner applied thereto;

Fig. 4 is a sectional view through the drain opening of the liner shown in Fig. 1;

Fig. 5 is a sectional view through the drain opening of the liner shown in Fig. 2;

Fig. 6 is a sectional view taken along the line VI—VI of Fig. 5;

Fig. 7 is a sectional view showing a modified form of the drain opening in the liner shown in Fig. 2; and

Fig. 8 is an enlarged perspective view showing a portion of the under surface of the liners illustrated.

Reference will now be had to Figs. 1 and 4 of the drawing wherein I have shown a liner, generally indicated at 10, constructed and arranged in accordance with my invention and applied to a kitchen sink. The latter includes a drain board 11 having a well or basin 12 formed in an intermediate portion thereof. The well 12 is defined by side walls 13 which extend downwardly from the drain board 11 and a bottom wall 14, the latter having a drain opening 15 formed therein (see Fig. 4). The drain opening 15 is connected in any well understood manner

2

to a trap or drain pipe 16. A backboard 17 extends upwardly from the rear margin of the drain board 11 and supports hot and cold water faucets shown at 18. The faucets 18 are provided with a conventional discharge spout 19 which may be swung horizontally to discharge water into different portions of the well or basin 12. As is well understood, the surfaces of the sink are usually covered with a vitreous enamel finish.

The liner 10 includes an apron 21 which is adapted to cover substantially all portions of the drain board 11 and which is provided with a well or basin 22 in an intermediate portion thereof. The basin 22 is defined by side walls 23 and a bottom wall 24, the latter having a drain opening 25 formed therein which communicates with the drain opening 15 of the sink. (See Fig. 4.) An upstanding bead 26 is formed on the liner peripherally of the apron 21 thereof to prevent the spillage of water over the edge of the liner.

The liner 10 is integrally molded or otherwise suitably formed of a resilient waterproof material such as, for example, natural or synthetic rubber. The liner is proportioned so that, when applied to the sink, the various portions thereof closely conform to the corresponding portions of the sink. Preferably, the apron portions 21 of the liner are held snugly in engagement with the drain board 11 by suction cups or recesses 27 (see Fig. 8) which are spaced apart on the under surface of the apron 21. It may be desirable to provide a series of suction recesses 28 on the bottom wall 24 of the liner around and adjacent the opening 25 thereof which will serve to hold the portion of the bottom wall 24 adjacent the opening 25 firmly in engagement with the bottom wall 14 of the sink, whereby the seepage of water between the bottom walls 24 and 14 of the liner and the sink is prevented.

In use, the liner 10 provides a cushioned working surface and prevents or substantially reduces breakage of china or glassware which may be accidentally dropped during washing thereof. Furthermore, this cushioned surface reduces clatter during the washing of tableware and pans usually caused by contact thereof with the hard vitreous finish on the sink. Chipping of the vitreous finish is prevented by the cushioning liner, which also prevents staining of the vitreous finish usually caused by acid in food, particularly citrus fruits. The liner may be provided in different colors or designs to match the decorations in the kitchen.

55 All surfaces of the liner and the vitreous sink

may be cleaned after the removal of the liner from the sink. The latter operation is effected by lifting the edges of the apron 21 so as to admit air to the suction recesses 27, after which the liner may be removed for cleansing. A hole 29 may be provided in one end of the liner so that it may be hung on a peg or hook to dry or while the sink is being cleansed.

In Figs. 2 and 5 to 7, I have shown a liner 30 having a center partition 31 and which may be applied to a single basin sink in order to provide a double basin sink arrangement. The partition 31 extends to the bottom of the liner 30 and is joined to the bottom wall 24 of the liner 30 to define a pair of basins 32 and 33 in the liner. In Figs. 5 and 6, I have shown a hollow neck 34 formed on the bottom wall 24 which is adapted to fit within the drain pipe 16 of the sink. A stiff reinforcing ring 35 may be molded in the neck 34 to stiffen the neck and assure its proper fit within the pipe 16. In this embodiment, the partition 31 extends downwardly to the bottom of the neck 34 so that respective drain openings 36 and 37 are provided for the basins 32 and 33. A suitable stopper 39, generally semicircular in cross section and shown in broken lines, may be provided for closing the openings 36 and 37. The liner 30 is otherwise constructed and used in the same manner as described in connection with the liner 10 shown in Fig. 1.

In Fig. 7, a different form of drain outlet is shown for the liner 30 (Fig. 2). The drain opening for the basins 32 and 33 is shown at 41 in the bottom wall 24. The partition 31 is joined to the bottom wall 24 and extends across the top of the opening 41. In this embodiment, as in Figs. 5 and 6, a stopper 39 may be employed to prevent draining of water from either basin 32 or 33 to the opening 41.

In Fig. 3, I have shown a liner 50 applied to a sink 51 having double basins 52 and 53. The liner 50 has a hollow center partition 54 which fits over the adjacent end walls 55 of the basins 52 and 53. The partition 54 defines a pair of basins 56 and 57 in the liner 50. In this embodiment, of course, each basin 56 and 57 will be provided with a drain opening similar to that shown at 25 in Fig. 4. The liner 50, otherwise, is constructed and employed in the same manner as disclosed in connection with the liners 10 and 30.

I have shown and described liners wherein the bottom walls 24 thereof closely engage the bottom walls 14 of the sink with registering drain openings 25 and 15, but it will be understood that the bottom wall 25 of the liner may be spaced above the bottom wall 15 of the sink so that the drain opening 25 in the liner may be arranged otherwise than in direct alignment with the opening 15 in the sink.

From the foregoing description, it will be apparent that I have provided, as a new article of manufacture, a liner for a sink which may be readily applied to and removed from the sink. Being of resilient construction, the liner will conform to the surfaces of the sink which it covers and snugly engage these surfaces. The cushioning provided by the resilient liner reduces the noise accompanying washing operations in the

sink, and the liner will prolong the life of a vitreous enamel sink by preventing chipping and staining of the vitreous finish thereon.

I have described my liner applied to a vitreous sink or one having a relatively expensive vitreous enamel finish. This would be the case where a liner were purchased for application to a sink already installed. However, my liner may be manufactured and sold as a part of a new low cost sink having a relatively inexpensive protective finish and would, therefore, provide an attractive, renewable cover for these sinks. Such liners could be renewed at low cost from time to time if they become damaged or if it becomes desirable to change the color of the liner in order to match any redecoration of the kitchen.

While I have shown my invention in several forms, it will be obvious to those skilled in the art that it is not so limited, but is susceptible of various other changes and modifications without departing from the spirit thereof.

What I claim is:

1. As a new article of manufacture, a liner for a sink structure having side walls and a bottom wall providing a well within the sink structure, said bottom wall having a drain opening therein, said liner including side walls and a bottom wall integrally formed of a resilient water-proof material and closely fitting within the well of the sink structure and a transverse wall integral with and connecting opposed side walls and the bottom wall of the liner for providing a pair of wells within the liner, said transverse wall having a portion thereof aligned above the drain opening of the sink and defining, with portions of the bottom wall of the liner, a pair of openings providing, respectively, communication between said wells of the liner and the drain opening of the sink structure.

2. As a new article of manufacture, a liner for a sink structure having side walls and a bottom wall providing a well within the sink structure, said bottom wall having a drain opening therein, said liner including side walls and a bottom wall integrally formed of a resilient water-proof material and closely fitting with the well of the sink structure, a transverse wall integral with and connecting opposed side walls and the bottom wall of the liner for providing a pair of wells within the liner, a generally cylindrical hollow neck extending downwardly from the bottom wall of the liner and closely fitting within said opening in the sink structure, said transverse wall having a portion thereof extending diametrically of and within the neck for defining a pair of respective drain openings for the wells of the liner.

ANDREW W. ROBERTSON.
